UNITED STATES PATENT OFFICE

NATHAN M. LOWER, OF BALTIMORE, MARYLAND, ASSIGNOR TO THE STANDARD STOKER COMPANY, INCORPORATED, A CORPORATION OF DELAWARE

LOCOMOTIVE STOKER

Original application filed July 2, 1928, Serial No. 289,774. Divided and this application filed October 5, 1929. Serial No. 397,681.

My invention pertains to locomotive stokers, and especially to the type of stokers, disclosed in my copending application Serial No. 289,774, filed July 2, 1928, of which the present application is a division, in which the fuel is fed, from a fuel forwarding device under the locomotive tender, direct to the fire box by a screw conveyor device operating in a conduit device which is disposed in a slightly inclined position and extends through the locomotive deck plate upward to the fire door; so that the feeding is easy and free, and there is little, if any, tendency to break up and pulverize the lumps of fuel.

It is an object of the present invention to produce a stoker of the above character in which the fuel forwarding device carried by the tender occupies a stationary position with respect to the latter, and the conduit portion carried by the locomotive occupies a stationary position with respect to such locomotive, while still providing for the relative movements between the locomotive and tender which occur when the latter are in use. A further object of the present invention is to provide a stoker of the above character which, while fully efficient, can be produced at relatively low expense, and can, in certain circumstances, be installed exceptionally economically.

One form of locomotive stoker constructed in accordance with my present invention is described in the following specification, and shown, in sectional elevation, in the accompanying drawing.

The stoker comprises a trough 10, located beneath the front end of the locomotive tender 11, so as to receive fuel downwardly therefrom. The front end of this trough is formed with a hollow partially spherical portion 12 upon which is mounted the corresponding portion 13 of the rear section 14 of a telescoping conduit 24, whereby the trough and rear section are connected by a hollow ball and socket joint, designated 15.

Upon the rear section 14 telescopes the front section 16 of the telescoping conduit 24, such front section having at its end a hollow spherical portion 17 seating in the correspondingly shaped portion 18 of a riser

conduit 19 fixed to the locomotive frame, so that the front section 16 and riser conduit 19 are connected by a ball and socket joint, designated 20.

For forwarding the fuel, a conveyor screw 21, suitably rotated, is mounted in bearings in the box 10 and is connected, at its front end, by means of a universal joint 22, to the rear section 23 of a telescoping shaft which is contained in the telescoping conduit 24. 60 Such rear shaft section is provided with a conveyor screw 25, and the front section 26 of the telescoping shaft may likewise be provided with a propeller portion 27. Such front section is connected, by a universal joint 28, with a conveyor screw 29 mounted in the riser conduit 19. 65

The socket portion 18 is secured to the locomotive frame beneath the deck plate 30 at the rear end of the latter; and the riser conduit 19 extends upward, at a gentle inclination, through the deck plate 30 to the opening 31 of the fire-box, where it opens upon a distributor plate 32, wherefrom the fuel is directed into the fire box by steam blast or the like. By this construction, the riser conduit is made to assume approximate alignment with the telescoping conduit 24; so that the fuel is forwarded in an even stream, with a minimum of liability to breaking up of the particles. The conveyor screw 29 extends up to the fire box opening 31, so that the fuel is delivered directly upon the distributor plate. 75 80

It will be noted that, by the above construction, not only is the riser conduit 19 permitted to remain stationary with respect to the locomotive,—thus avoiding the inconveniences and dangers that would attend a riser conduit which would move about, in the locomotive cab, in accordance with the relative movements between the locomotive and tender,—but the trough 10 is permitted to remain stationary with respect to the tender, which latter is an advantage in many circumstances. 85 90 95

As an entirely new unit, the whole stoker can be produced at a relatively low cost. But a number of the parts of the stoker,—those to the rear of the riser conduit 19,—are the same as, or similar to, elements of old stokers 100

which will be replaced by the stokers of my invention. When such an old stoker is in place upon a locomotive to be equipped with a stoker of my invention, this makes the installation of the new stoker a matter of exceptional economy; since a number of the elements of the old stoker may be retained as parts of the new device.

I claim:

1. In a device of the class described, a locomotive having a firebox including a backwall provided with a firing opening and firing deck extending rearwardly from the backwall, a tender behind the locomotive including a fuel bin, and a mechanical stoker comprising a trough rigidly mounted on the tender below the level of the firing deck and in open communication with the bin to receive fuel therefrom, a substantially straight conduit rigidly mounted on the locomotive and extending upwardly and forwardly from a position immediately below and closely adjacent to the rear end of the firing deck and delivering directly to said firing opening from its forward end, an intermediate telescopic conduit flexibly connected in end to end relation with the adjacent ends of the trough and the rigidly mounted conduit, said intermediate conduit inclined upwardly from said trough and said rigidly mounted conduit inclined upwardly from said intermediate conduit, the tangent of the angle between the rigidly mounted conduit and the horizontal being less than the cotangent of said angle, a screw in said trough and in each of said conduits for advancing fuel to the firing opening, and means for distributing the fuel in the firebox.
2. In a locomotive having a firebox provided with a backhead having a firing opening therein, a cab having a deck, and a tender provided with a deck; nozzles for producing fluid jets positioned adjacent said opening, a stoker conduit assuming a general direction forwardly and upwardly from beneath the tender deck to said nozzles and comprising conduit sections arranged angularly in relation to each other, said stoker conduit having a conduit section securely attached to the backhead in communication with said opening and sloping forwardly and upwardly from a point adjacent the cab deck to said nozzles and having its bottom inside surface substantially straight along the medial vertical plane of the conduit section, a conduit section rigidly mounted in the tender, an intermediate conduit section flexibly connecting the first two named conduit sections, and a fuel conveyor within said stoker conduit composed of screw sections, universally jointed together substantially adjacent the respective junctions of the angularly arranged conduit sections, said conveyor extending substantially throughout the entire length of said stoker conduit.

3. In a locomotive having a firebox provided with a backhead having a firing opening therein, a cab having a deck, and a tender provided with a deck; nozzles for producing fluid jets positioned in the firebox at or forward of the inside surface of the backhead, a stoker conduit assuming a general direction forwardly and upwardly from beneath the tender deck to said nozzles and comprising conduit sections arranged angularly in relation to each other, said stoker conduit having a conduit section securely attached to the backhead in communication with said opening and sloping forwardly and upwardly from a point adjacent the cab deck to said nozzles, a conduit section rigidly mounted in the tender, an intermediate conduit section flexibly connecting the first two named conduit sections, and a fuel conveyor within said stoker conduit composed of screw sections universally jointed together substantially adjacent the respective junctions of the angularly arranged conduit sections, said conveyor extending substantially throughout the entire length of said stoker conduit.

In testimony whereof, I sign my name.
NATHAN M. LOWER.
